COMBINED SOFA AND TABLE OR SIMILAR ARTICLE

Gene Gelbspan and Willard H. Cohen, Winnetka, Ill.

Application February 25, 1957, Serial No. 44,962

Term of patent 14 years

(Cl. D15—11)

The characteristic features of my design are shown by means of solid lines in the drawing, the dotted lines in the upper part of Figure 1 and elsewhere being for illustrative purposes only.

We claim:

The ornamental design for a combined sofa and table or similar article, substantially as shown and described.
